Primary Examiner — Elizabeth J Oswecki(74) *Attorney, Agent, or Firm* — Quickpatents, LLC;
Kevin Prince(57) **CLAIM**

The ornamental design for a fully masked protective jacket, as shown and described.

DESCRIPTION

FIG. 1 is a perspective view of a fully masked protective jacket, showing my new design with the hood in a closed position;

FIG. 2 is a front elevational view of FIG. 1;

FIG. 3 is a rear elevational view of FIG. 1;

FIG. 4 is a left side elevational view of FIG. 1;

FIG. 5 is a right side elevational view of FIG. 1;

FIG. 6 is a top plan view of FIG. 1;

FIG. 7 is a bottom plan view of FIG. 1;

FIG. 8 is a perspective view of FIG. 1, with the hood in an open position;

FIG. 9 is a front elevational view of FIG. 8;

FIG. 10 is a rear elevational view of FIG. 8;

FIG. 11 is a left side elevational view of FIG. 8;

FIG. 12 is a right side elevational view of FIG. 8;

FIG. 13 is a top plan view of FIG. 8; and,

FIG. 14 is a bottom plan view of FIG. 8.

The broken lines in the figures depict portions of the jacket that form no part of the claimed design.
